UNITED STATES PATENT OFFICE.

EDWARD F. DUDLEY, OF OAK PARK, ILLINOIS, ASSIGNOR TO MIEHLE PRINTING PRESS AND MANUFACTURING COMPANY, OF CHICAGO, ILLINOIS, A CORPORATION OF ILLINOIS.

REGISTRATION-FEED-BOARD-OPERATING MECHANISM.

Application filed March 3, 1921. Serial No. 449,513.

To all whom it may concern:

Be it known that I, EDWARD F. DUDLEY, a citizen of the United States, residing at Oak Park, in the county of Cook and State 5 of Illinois, have invented certain new and useful Improvements in Registration-Feed-Board-Operating Mechanisms, of which the following is a specification.

My invention concerns a novel type of operating or actuating mechanism for the feed 10 or registration boards or platforms of printing-presses or similar machines, wherein the movement of the board registers the sheet borne by it with or causes its edge or edges 15 to engage one or more suitable stop or abutment gauges or guides.

In printing-presses it is customary to employ a plurality of front guides or gauges against which the forward edge of the sheet 20 is brought to bear and a side gauge or guide employed in a similar way for the corresponding edge of the sheet, whereby the latter is shifted into proper and correct position relative to the impression-cylinder preliminary 25 to its temporary gripping or fastening to the latter during the printing operation.

In such machines it is usual to have side 30 gauges or guides at opposite sides of the board with suitable operating means, whereby either side edge of the sheet may be brought into accurate and true register with its corresponding guide.

Such capability of shifting the sheet laterally 35 into register with either one of the two opposite side guides or gauges is particularly useful when sheets are printed on both sides enabling the registration to take effect in both printing operations with respect to the same edge of the sheet.

The present invention pertains to improvements in the means for moving the feed or registration board to carry the sheet against the proper guide and concerns more 45 particularly improved instrumentalities for modifying or changing the action of such board actuating mechanism whereby it may register the sheet with either one of the pair of opposed side guides.

50 In the accompanying drawing I have shown a desirable and convenient embodiment of such reversible registration-board

operating mechanism, the same reference characters applying to like parts throughout the several views.

In the drawing:

Figure 1 is a plan view of the actuating mechanism for the registration board, the side guides being illustrated, but the board itself is not shown;

Figure 2 is a similar view with the elements of the mechanism in a different position and adapted to feed the paper sheet to the other side guide;

Figure 3 is a fragmentary end elevation 65 of the complete appliance illustrating more specifically the means employed for reversing the operation of the board;

Figure 4 is a view similar to Figure 3 with the parts coupled up to register the sheet 70 with the opposite side guide; and

Figure 5 is an enlarged plan detail view of such reversing means.

As will be readily seen from the drawing, the appliance includes a sloping or inclined 75 bodily-movable registration-board or feed-platform 11 mounted for movement on the top of a hollow shell or casing 12 internally supplied with cross webs or ribs 13 and 14.

The paper sheets are delivered to the top 80 surface of such board by a reciprocatory suction-feeder 15, mounted on power-actuated bent rock-arms 16, which picks up the top sheets in succession from a stack or pile, not illustrated, and conveys or transports them one by one to and drops them on to the board, the suction of the feeder to control its sustaining effect on the sheet being governed by a valve of any approved form, not shown.

The sheet having been delivered to or deposited on the board, the latter moves in a general oblique direction to register it with one or more front gauges 17 and with either one of two opposite side gauges 18 and 19 95 depending upon which side of the sheet is to be registered.

To effect this result, mechanism is provided to move the board and its sheet in the general diagonal direction specified, whereby the front edge of the sheet is first brought against the gauge or gauges 17 and then one side edge is shifted into contact with one or the other of the side gauges 18 and 19, as

the case may be, without withdrawing it from or disturbing its correct register with the front gauge.

The current invention resides in the mechanism for shifting or moving the board to effect or accomplish its sheet registering function and concerns more particularly the means for reversing the action of such operating mechanism whereby either side guide 10 or gauge may be rendered operative.

It is desired to give the board a bodily movement first forwardly and then laterally or transversely without wholly stopping its forward travel whereby to assure 15 the maintenance of contact of the edge of the sheet with the front gauge during the securing of its register with the side gauge.

To this end a parallel-motion mechanism is supplied comprising a suitably-guided 20 sliding rack 21 reciprocated by an oscillatory gear 22 rockingly mounted in a bearing in the web 13.

Such rack is provided with two sets or groups of supplemental or auxiliary teeth 23 25 and 24 in mesh respectively with properly-mounted oscillatory gears 25 and 26 each equipped with an arm 27 having at its end an upstanding pin 28 with a pivotal mounting in the feed or registration board.

30 At its opposite side gear 22 coacts with another small gear 29 supplied with a like arm 27 having a pivotal connection at its end with the board, the teeth of such gear being in mesh with those of a rack 31 which 35 at its other end operates a gear 32 likewise provided with an arm 27 and its pivot pin 28.

Obviously, the oscillation of gear 22 will 40 simultaneously rock all four arms 27 thereby moving the board in a parallel-motion manner first toward the front gauge or gauges and then toward one of the side gauges.

To operate gear 22 and the elements above described coupled to or affiliated with such 45 gear, it is equipped with an arm 33 connected by a link 34 to one arm 35 of a three-armed lever 35—37—38 fulcrumed at 36 and supplied near the ends of its two opposite arm portions 37 and 38 with outstanding pins or lugs 39 and 41, either one of which is adapted and designed to fit in an aperture or bearing in the upper end of an upright link 42 pivotally connected at its lower end to an oscillatory arm 43 on a rock-shaft 44, the 50 link 42 being pulled toward the lever by a coil contractile spring 45 having one end connected to the link and its other end secured to any convenient and suitable part of the machine framework.

60 When link 42 is connected to the pin 39 of arm 37, being held against the arm by the

pulling action of spring 45, it is designed by its lengthwise strokes to oscillate the plurality of arms 27 from their original positions, as shown in Figure 1, down about 65 90 degrees and then back to their initial positions, in so doing operating the board in the manner described to register its sheet with both the front and side gauges.

Under these circumstances the side gauge 70 18 only is operative.

If, instead of using gauge 18, it is desired to employ the other side gauge 19, link 42 is slipped off of pin 39 against the action of spring 45, the lever 35—37—38 rocked on its 75 fulcrum sufficiently to permit the application of the link to the other pin 41, and the link so coupled up to the lever, such turning of the lever having rocked the several arms 27 into the positions shown in Figure 2 ready 80 to carry the board in a direction to register the sheet with the one or more front gauges and the side gauge 19.

Now the strokes of the link will rock the 85 arms 27 from their initial positions depicted in Figure 2 to positions about 90 degrees therefrom and back again, the registration-board moving correspondingly and carrying 90 its sheet into register with the front gauges and the side gauge 19.

The simple means illustrated and described are effective in operation and may be easily actuated, or modified to change the mode of action of the machine. The mere movement of the parts to permit the coupling of the elements together assures that the members which directly move the board 95 will be in correct position for doing the work they are designed to perform.

The invention is not necessarily limited to 100 this particular embodiment but comprises all changes fairly falling within the scope of the appended claim defining the invention.

I claim:

In a sheet-registration appliance of the character described having a movable registration-board adapted to bear the sheet, operating means for said board including a lever having pins outstanding from its side on opposite sides of its fulcrum, an apertured link designed to actuate said lever by receiving the one or the other pin in said aperture, and a spring yieldingly pulling 110 said link toward said lever to maintain operative the pin and hole connection between the parts, whereby a selective registration movement of the board may be had by rendering the one or the other connection operative between the link and lever, substantially 115 120 as described.

EDWARD F. DUDLEY.
